United States Patent Office

Des. 183,939
Patented Nov. 18, 1958

183,939

DECANTER

Raymond F. Loewy, New York, N. Y.

Application November 18, 1957, Serial No. 48,513

Term of patent 14 years

(Cl. D58—8)

FIG. 1

FIG. 2

Fig. 1 is an elevational view of a decanter in exploded position; and

Fig. 2 is an elevational view thereof in closed position, showing my new design.

The cap and base portions are opaque and contrast in appearance with the transparent body portion of the decanter.

I claim:

The ornamental design for a decanter, as shown and described.
